UNITED STATES PATENT OFFICE.

JAMES A. ROBERTS, OF DETROIT, MICHIGAN, ASSIGNOR TO THE ROBERTS DUPLEX PLANING MACHINE TOOL COMPANY, OF SAME PLACE.

CUTTER-HEAD.

SPECIFICATION forming part of Letters Patent No. 311,679, dated February 3, 1885.

Application filed September 17, 1884. (No model.)

To all whom it may concern:

Be it known that I, JAMES A. ROBERTS, of Detroit, in the county of Wayne and State of Michigan, have invented new and useful Improvements in Cutter-Heads; and I hereby declare that the following is a full, clear, and exact description thereof, reference being had to the accompanying drawings, which form a part of this specification.

10 This invention relates to an improvement in the construction of and means for securing tools to cutter-heads, and the invention is more specifically intended to apply to the cutter-heads of a planing and matching machine for 15 which I have heretofore applied for Letters Patent.

The invention consists in the combination of the beading and tonguing knives with retaining-caps for securing each one to the cutter-head, said caps being recessed in conformity to the cutting-faces of said knives, as more fully hereinafter set forth and claimed.

In the drawings, Figure 1 is a perspective view of two cutter-heads, with planing, tonguing, and beading knives secured thereto and shown in operation; and Fig. 2 is a sectional detail of the same.

A is the ordinary cutter-head in present use in planing-machines.

30 B are tonguing-knives, intended to form a tongue upon the inner edges of the boards C, which are separated by a division-plate, D.

E are other knives, intended to round the inner edges of the tongues.

35 F are beading-knives for making the usual center bead in ceiling, and G are the ordinary planer-knives.

The planer-knives are of the ordinary description, and are secured to the cutter-head in 40 the usual way. The tonguing and beading knives are of uniform cross-section throughout, the cutting-face of said cross-section, being of any desired configuration varying from a straight line, so that when the tool is ground in the usual manner the cutting-edge shall present just the required outline.

45 H are caps for securing the tonguing and beading tools in place upon the cutter-head without the use of slots in the tools. These 50 caps are recessed upon their under side in ex-

act conformity with the shape of the knife, the recess, however, being made a trifle shallower, so that when the caps are secured by means of the bolts I and nuts J the caps will clamp the knives to the cutter-head. The bolt I is provided with a head, K, by which it is retained in the lateral grooves L of the cutter-head.

55 The afore-described construction of the knives and the manner of securing them in place has the advantage that the cutter-head 60 may always carry all the necessary knives for making either flooring or ceiling. Those knives which are not used for one of the two operations may be made inoperative by loosening the nut J, retracting the knife, and then 65 tightening the nut again. Another advantage is that the knives are fit for use until there is nothing but a short stump of the material left, while with the ordinary construction a good deal of material is wasted by the knife becoming 70 soon too short for use by repeated grinding.

I am aware that it is not new to secure beading-knives to cutter-heads by a recessed retaining-cap and bolt, the head of said bolt running in an undercut groove in the face of the cutter-head, and I do not claim such as my invention, for in all such constructions that I am aware of the recess in the retaining-cap 75 has not been in conformity to the shape of the cutting-face of the knife when the latter has said face varying from a straight line running crosswise thereof. The disadvantage of this construction is that where the retaining-cap only contacts with the elevated or raised portions of the cutting-face of the tool said portions become marred and unfit for use, and the tool cannot be used throughout its entire length, and, besides, the tool is more liable to slip when in operation, thereby causing a serious 80 delay or destruction of property. All these objections are eliminated by my improvement, as the retaining-cap is recessed to fit the contour of the cutting-face of the knife, thereby causing a contacting of every element of the 85 two surfaces and affording a large frictional contact, thus avoiding a marring or spoiling of the cutting-face of the tool and overcoming the liability of its slipping.

90 95 What I claim as my invention is—

The combination of a cutter-head having undercut lateral grooves or mortises upon its face, the nut J, retaining-bolt I, and a knife having its acting face varying from a straight line and uniform in cross-section throughout its whole length, with a retaining-cap recessed upon its under side in conformity to the shape of the cutting-face of the knife, all construct-

ed and arranged substantially as described, whereby an increased frictional surface is secured between the tool and cap, as set forth.

JAMES A. ROBERTS.
